(57) **CLAIM**

The ornamental design for a sander/polisher attachment for vacuum cleaners, as shown.

DESCRIPTION

FIG. 1 is a perspective view of a sander/polisher attachment for vacuum cleaners showing our new design;

FIG. 2 is a left-side elevational view thereof;

FIG. 3 is a front elevational view thereof;

FIG. 4 is a rear elevational view thereof;

FIG. 5 is a right-side elevational view thereof;

FIG. 6 is a top view thereof; and,

FIG. 7 is a bottom view thereof.

The broken line showing of a battery pack is for the purpose of illustrating portions of the sander/polisher attachment and forms no part of the claimed design.
